MEANS FOR APPLYING PLATFORMS AND
TURNING THE TOE ENDS OF PLAT-
FORM COVERSPaul W. Senfleben, Malden, Mass., assignor to
United Shoe Machinery Corporation, Flemington, N. J., a corporation of New Jersey

Application March 9, 1950, Serial No. 148,652

13 Claims. (Cl. 12—1)

1

This invention relates to machines for use in the manufacture of shoes and it is herein disclosed as embodied in a machine for adhesively incorporating platform units into partially completed shoes and also for turning the toe portions of the platform covers of such shoes. Some of the instrumentalities of the machine shown herein which are used in connection with the adhesive attaching of the platform units are similar to corresponding instrumentalities disclosed in United States Letters Patent No. 2,623,223, granted December 30, 1952 on my copending application.

In the manufacture of platform shoes it is a simple matter to turn the heel end of the platform cover into right side out position before (rather than after) the attaching of the platform unit, and then to attach the platform unit before (rather than after) the turning of the toe end of the platform cover.

It is an object of the present invention to provide a machine for performing the operations above mentioned, except the turning of the heel portion of the platform cover, with a minimum of handling of the shoe. To this end, and in accordance with a feature of the invention, the illustrated machine comprises a guideway along which a shoe support is movable between two stations, with means at one of the stations for facilitating the attaching of the platform unit and means at the other station for turning the toe portion of the platform cover. This same guideway is utilized also to permit the shoe support to be moved toewardly while the heel portion of the platform cover is held back to facilitate the laying of the platform unit in proper position upon the sock lining. After the platform unit is thus laid, it is cemented to the sock lining by the application of pressure. The shoe support is then slid along the guideway to bring the toe end of the shoe into operative relation to the platform cover turning instrumentalities.

These and other features of the invention, including details of construction, will now be more particularly described with reference to the accompanying drawings, in which

Fig. 1 is a front elevation of the head of a machine embodying the invention;

Fig. 2 is a plan view of a part of the mechanism shown in Fig. 1;

Fig. 3 is a plan view of a device for forming the heel portion of the platform cover of a shoe;

Fig. 4 is a section taken on the line IV—IV of Fig. 1;

Fig. 5 is an angular view of a shoe support;

2

Fig. 6 is a sectional view taken on the line VI—VI of Fig. 1;

Fig. 7 is a view of the parts shown in Fig. 6 looking in the direction of the arrow A;

Fig. 8 is a front elevation of a portion of the machine showing a platform unit being pressed upon the sock lining of a shoe;

Fig. 9 is a front elevation of a portion of the machine showing the toe portion of the platform cover being turned;

Fig. 10 is an end elevation showing the device for turning the toe end of the platform cover;

Fig. 11 is a sectional detail view showing how the toe end of the platform cover is turned;

Fig. 12 is a sectional detail view showing the position of the toe end of the platform cover after it has been turned;

Fig. 13 is a front elevation of a modified form of the machine;

Fig. 14 is a plan view of the mechanism shown in Fig. 13;

Fig. 15 is a front elevation of the machine shown in Figs. 13 and 14 illustrating the operation of forming the heel portion of the platform cover; and

Fig. 16 is an angular view of the turning horn used in both forms of the machine.

The machine illustrated herein is shown as operating upon a partially completed platform shoe of the open toed and open heeled type consisting of an upper U, a platform cover C, and a sock lining S united by stitching and mounted upon an inverted last L (Figs. 1, 11, and 12). The heel end of the platform cover has already been turned up to form a pocket; the toe end is still down in wrong side out position. The operations to be performed consist in preparing the shoe for the laying of a platform unit P (Figs. 8, 9, 13, 14, and 15) in proper position upon the sock lining, in applying pressure to the platform unit to cause pre cemented surfaces of the platform unit and the sock lining to adhere, and in turning the toe portion of the platform cover to right side out position. The platform unit P may consist of a platform of cork composition or other suitable material and may include also a wood heel H attached to the platform by staples St. as shown in Figs. 9, 14, and 15, or attached by cement or other means. The heel may be made integral with the platform in some types of shoes, or it may be omitted.

The operating instrumentalities of the illustrated machine consist of a shoe support 20 (Figs. 1, 5, 8, 13 and 15) movable along an undercut guideway 22 (Figs. 6, 8 and 15), a device 24 (Figs.

1, 8, 8 and 15) for centering the shoe, mechanism 26 (Figs. 1, 8, 13 and 15) for moving the shoe support toewardly along the guideway, alternative devices 28 (Figs. 1 and 3) or 30 (Figs. 13, 14 and 15) for holding back the heel portion of the platform cover while the shoe is being moved toewardly, a device 32 (Figs. 6, 7 and 8) for pressing the platform unit upon the sock lining to cause adhesion, and a device 34 (Figs. 1, 9, 10, 11 and 13) for turning the toe portion of the platform cover. The term "toeward" is used herein to denote the direction from the heel of the shoe, when mounted on the machine as shown, toward the toe of the shoe; and the term "heelward" is used to denote the reverse direction. The supporting structure of the machine comprises a column 36 adapted to rest upon the floor and to support a rigid head or frame 38 in which is formed the guideway 22.

The shoe support 20 includes an upstanding last pin 40 (Figs. 1, 5 and 13) and a toe rest 42 (Figs. 1, 6, 8, 9, 13 and 15). The last pin 40 has a collar 43 for supporting the cone of the last, and is secured in a block 44 having side flanges which are arcuate for engagement with an arcuate guideway formed in a block 46. The axis of this guideway is horizontal and transverse to the guideway 22 and it intersects the axis of the last pin 40 at about the level of the heel seat of the last L. The arcuate side flanges of the block 44 are retained in the arcuate guideway by overlapping portions of arcuate retaining strips 48 secured to the block 46. The block 44 (Fig. 5) is urged yieldingly in a heelward direction in its arcuate guideway by a coil tension spring 50, the heelward limit of movement of the block being determined by a stop 52 adjustably clamped to the block by a screw 53 and having a laterally extending lug engageable with a forward face of the block 46. The block 46 has a downwardly extending tongue 54 which slidably engages a transverse groove 56 formed in a slide 58. This slide 58 is freely slidable by hand along the guideway 22, and it can be urged toewardly by a treadle operated mechanism, later to be described, which acts on a pair of anti-friction rolls 60 which are mounted for idle rotation upon a pair of pins secured in alined bosses 62 extending transversely from the block 46.

The toe rest 42 (Figs. 1, 2 and 15) comprises a cylindrical pad of rubber mounted upon a horizontal transverse pin 64 which is carried by a yoke 66. The rubber pad 42 does not rotate while in operation but it clamped in a fixed position from which it can be unclamped to permit turning to bring a fresh portion into working-engaging position. The yoke 66 has a depending stem 68, the lower portion of which is threaded and which slidably engages a non-threaded bore formed in a boss 70 upstanding from a slide 72. A knurled nut 74 threaded upon the lower portion of the stem 68 rests upon the upper end of the boss 70 to adjustably determine the heightwise position of the toe rest pad 42. Turning movement of the pad is prevented by a screw 76 (Fig. 15) threaded through the wall of the boss 70 and having a reduced end which loosely engages a heightwise slot 78 formed in the stem 68. The slide 72 is slidable along the guideway 22 and is yieldably connected to the slide 58 by a coil compression spring 80 surrounding a longitudinal rod 82. The ends of the spring 80 bear respectively against the slides; the rod 82 is secured to the slide 72 and extends slidably through the slide 58. As shown in Fig.

5, the tongue 54 of the block 46 is recessed to provide clearance for the rod 82 as the block 46 moves laterally. A head 84 formed on the heelward end of the rod 82 and engaging the heelward end surface of the slide 58 retains the slides 72 and 58 in their normal position of maximum separation. The purpose of thus yieldably connecting the slide 72 to the slide 58 is to permit advance of the shoe toewardly beyond the locality at which the slide 72 is stopped by the interference of other parts of the machine.

The centering device 24 comprises a plate 86 (Figs. 1, 2, and 13) in which is formed a V-shaped notch (the apex of which is blunted) having a pair of converging cam surfaces 87 for engagement with the heel end of the shoe or of the last upon which the shoe is mounted. This plate 86 is mounted upon a pair of coaxial pins 88 carried by a pair of ears 90, the plate having a limited freedom of self-adjusting tilting movement heightwise about the axis of the pins 88. The ears 90 extend from the forward ends respectively of a pair of parallel slide bars 92 which are guided for longitudinal movement in a pair of bearings 94. The heelward end portions of the slide bars 92 are rigidly connected by a cross bar 96 to insure movement of the slide bars in unison. Surrounding each of the slide bars 92 and bent over the heelward end of the plate 86 is a washer 98. These washers constitute abutments for a pair of compression springs 100 which surround the slide rods 92 respectively and which bear against the toeward ends of the respective bearings 94. The bearings 94 are integral with a block 102 which carries transverse trunnion pins 104 upon which the block 102, the slide rods 92, and the centering plate 86 are fulcrumed for heightwise tilting movement, the trunnion pins 104 being journaled in a pair of slide walls 106 of a stationary bracket 108 secured upon the heelward end of the head 38. Integral with one of the bearings 94 is a depending web 110 having a lug 111 through which is threaded a stop screw 112. The end of the screw 112 bears against an abutment surface 114 formed on a portion of the bracket 108 and is yieldingly held against said surface by a tension spring 116. The operating height of the centering plate 86 can readily be adjusted by turning a knurled head of the screw 112. If desired, the block 102 together with the plate 86 can be clamped in any chosen position of heightwise pivotal adjustment by a winged screw 118 threaded into the web 110 and extending through an arcuate slot 122 formed in the adjacent side wall 106.

The mechanism 26 for advancing the shoe support toewardly includes a pair of parallel upstanding arms 124 (Figs. 1, 2 and 4) which are pivotally mounted for free rotation upon a transverse shaft 126. The arms 124 are rigidly connected by an integral cross bar 128 which insures their movement in unison. The shaft 126 is journaled in bearings 130 (Fig. 4) formed in the side walls of the head 38. Integral with one of the arms 124 is a bell crank arm 132 (Fig. 1) to the free end of which is pivotally connected the upper end of a treadle rod 134. A tension spring 136 secured at its lower end to the treadle rod 134 and anchored at its upper end to a bracket 138 secured to the head 38 holds the treadle rod up in a stopped position determined by the engagement of the arms 124 with the bracket 108. When a treadle (not shown), which is connected to the lower end of the rod 134, is depressed, the arms 124 will swing toewardly and will come into

simultaneous engagement with the rolls 60 and continued depression of the treadle will urge the shoe support 20 toewardly.

The device 28 for holding back the heel portion of the platform cover while the shoe is being moved toewardly includes a U-shaped horn 140 (Figs. 1 and 3) of spring sheet metal. The horn 140 is fixed upon a supporting block 142 which is secured upon the upper end of a rod 144. This rod 144 inclines downwardly and heelwardly and is guided for sliding movement in a bore formed in a boss 146 which is integral with the bracket 108. Formed upon the lower end of the rod 144 is a square block 148 which is pivotally connected to the upper end of a link 150. The lower end of the link 150 is pivotally connected to an operating handle 152 (Fig. 4) which is fulcrummed upon a stationary pin 154 secured in a bracket 156 depending from the head 38. Secured upon the shaft 126 by a pin 158 is a sleeve 160 having a pair of inclined arms 162 which embrace the block 148. Formed in the upper ends of arms 162 are slots 164 which engage the end portions of a transverse pin 166 extending through the block 148. Fixed upon an end portion of the shaft 126 by a pin 168 is a crank arm 170. A snap acting tension spring 172 has one end anchored to the bracket 138 and the other end hooked over a pin 174 on the crank arm 170. It is evident that when the horn 140 is in the up position as shown in Fig. 1, it will be held in that position by the spring 172 because the axis of the spring is above the axis of the shaft 126. When the horn 140 is in its down position, as will later be explained, the axis of the spring 172 will pass below the axis of the shaft 126 and the spring will thus serve to hold the horn in its down position. This down position of the horn, when no shoe is on the shoe support, is adjustably determined by a knurled nut 176 threaded upon the upper portion of the rod 144 and engageable with the upper end surface of the boss 146. The up position of the horn 140 is determined by the engagement of the handle 152 with the head 38.

After the horn 140 has been lowered from its initial position as shown in Fig. 1 to a position wherein its lower edge rests upon the sock lining S, it is expanded to a width sufficient to enable the heel portion of the platform unit to be placed within it. Such expansion is effected by means of a pair of spreader arms 180 (Fig. 3) pivotally mounted upon fulcrum pins 182 secured in the block 142. The toeward end of each arm 180 has formed in it a bearing which engages an upstanding pin 184, the lower portion of which is secured to the horn 140. Extending heelwardly from each arm 180 is a grip handle 186. Intermeshing gear sectors 188 coaxial with the pins 182 are formed upon the respective spreader arms 180 to insure the coordination of the movements of the spreader arms about a common center. The spreader arms 180 are normally held in a closed position by compression springs 190 interposed between the block 142 and the respective grip handles 186. To open or spread the horn 140, the handles 186 are brought closer together and they can be held in any desired position by a latch 192 which is pivotally mounted upon a pin 194 carried by one of the handles 186. A rod 196, pivotally mounted upon a pin 198 carried by the other handle 186, passes through an opening in the latch 192 and is cramped in the latch by a compression spring 200 interposed between the adjacent handle 186 and a tail 202 of the latch.

The device 32 (Figs. 6, 7, and 8) for pressing the platform unit upon the sock lining to cause adhesion includes a pad 204 of rubber or other suitable material backed by a metal disk 206. 5 This disk 206 is mounted for angular self-adjustment by means of a ball and socket joint 208 on the lower end of a stem 210 which is secured in a bar 212. A compression spring 214 surrounding the stem 210 and interposed between the bar 212 and the disk 206 normally holds the disk in a neutral angular position from which it can tilt upon engagement with the work. Secured to the bar 212 above the pad 204 is a hand grip 216 by means of which the operator 10 can exert directly upon the work pressure which is additional to that which he exerts through the machine. As shown in Fig. 8, the pad 204 engages the forepart of the platform P to press the platform against the sock lining of the shoe. 15 The device 32 includes also a rod 218 having a rounded lower end for engagement with the heel H, the rod being guided for purposes of adjustment in a socket formed in a boss 220 on the bar 212. A knurled head 222 secured on a stem 224 which extends up from the rod 218 and which is threaded in a bore in the boss 220 provides for adjustment of the operating position of the rod. The bar 212 carries a third presser member in the form of a transverse bar 226 engageable with the shank portion of the heel H and pivotally mounted for limited swinging movement of self-adjustment upon a pin 228 carried by a lug 230 on the bar 212, said pin extending longitudinally of the shoe. 20 The bar 212 is pivotally mounted, for equalization of pressure, upon a shouldered screw 232 secured in the upper end of a lever 234 comprising a pair of parallel arms. A stop pin 236 extending from the lever 234 and engageable with 25 an arcuate slot 238 in the bar 212 limits the freedom of swinging movement of the bar about the pivot screw 232. The lever 234 (Fig. 6) is fulcrummed upon a stationary pin 240 which is mounted upon a pair of walls 242 of a bracket 244. 30 This bracket 244 is mounted upon a bracket 246 which is secured to the head 38. The lever 234 has a portion 248 extending below the fulcrum pin 240 and carrying a pivot pin 250 to which is connected one end of a toggle link 252. The other end of the toggle link 252 is pivotally connected by a pin 254 to the upper end of a second toggle link 256. The lower end of the toggle link 256 is pivotally connected by a pin 258 to a slide 260 having ratchet teeth 262. The slide 260 is guided for heightwise movement in a guideway formed in a boss 264 on the bracket 246 and is retained in its guideway by a cover plate 265. The lower end portion of the toggle link 256 is forked to embrace the boss 264, the side walls of the boss having heightwise slots through which the end portions of the pin 258 extend. A compression spring 266 housed in the boss 264 and backed by an abutment screw 268 normally holds the slide 260 up to a limiting position determined by a stop link 270. 35 This stop link 270 has a forked end which is pivotally connected by a pin 272 to the toggle link 256 and it has a shank which slides freely through a bore in a swivel pin 274. The end portions of the swivel pin 274 are journaled for free turning in bearings formed in the bracket walls 242. When the pressing device 32 is in its up position, as shown in solid lines in Fig. 6, a shoulder 276 on the stop link 270 engages the swivel pin 274 to hold the toggle link 256 against 40 movement to the right, while the spring 266 ex-

erts an upward thrust against the toggle link 256 which holds the toggle link in its stopped position with the pin 254 to the right of dead center, i. e., the line joining the axes of the pins 240 and 258.

The pressing device 32 is moved from its up position down into operative position (indicated by dash-dot lines in Fig. 6) by an operating handle 278 fulcrumed on the pin 240 and having an integral forked offset depending portion 280 which is pivotally connected by a pin 282 to one end of a link 284, the opposite end of which link is pivotally connected by a pin 286 to the toggle link 256. Movement of the handle 278 to the right (as seen in Fig. 6) causes the toggle link 256 to move to the left past the dead center line already mentioned, and continued movement of the handle causes the toggle formed by the links 252 and 256 to straighten into the position shown in dash-dot lines in Fig. 6. Movement of the toggle to the left is limited by a stop collar 288 on the link 270 and engageable with the swivel pin 274 just after the toggle pin 254 has passed to the left of a dead center line joining the centers of the pins 250 and 258.

The movement of the pressing device 32 into its down position causes the slide 260 to descend against the up-thrust of the spring 266. Such descent is limited by a pawl 290 pivoted upon a pin 292 fixed in the bracket walls 246. The pawl 290 has a tooth 294 which, when the pawl is swung to the left by a spring 296 connecting it to the toggle link 256, will engage the ratchet teeth 262 to prevent further descent of the slide 260. Continued downward pressure upon the handle 278 will then cause the straightening toggle link 252 and 256 to exert a positive upward thrust against the left end of the lever 234, thereby causing the pad 204, the rod 218, and the bar 226 to bear down upon the platform unit. The extent of downward movement of the slide 260 is determined by a stop screw 298 adjustably threaded into the pawl 290 and having a head engageable with the toggle link 256. When the effective length of the stop screw 298 is shortened, engagement of the tooth 294 will take place sooner and a relatively great pressure will be exerted through the toggle mechanism; and when the effective length is increased, engagement will take place later and a relatively less pressure will be exerted.

The device 34 for turning the toe portion of the platform cover includes a pad 300 (Figs. 1, 9, 10, and 11), preferably of a hard plastic material, for bearing down upon the toe portion of the platform P. This pad 300 cooperates with a stationary turning horn 302 which engages between the platform cover C and the last L (or upper U for a shoe with a closed toe). The pad 300 is backed by a metal plate 304 which is fixed upon a shaft 306 having its end portions journaled for limited turning in bearings 308. Threaded upon reduced end portions of the shaft which extend out beyond the bearings 308 are retaining nuts 310. One of the bearings 308 is recessed to receive a stop pin 312 (see Fig. 10) extending radially from the shaft 306 and engageable with the ends of the recess in the bearing to limit turning of the shaft. The bearings 308 are mounted respectively upon the upper ends of a pair of vertical slide rods 314 which are movable heightwise in unison. A tension spring 316 has its upper end hooked over a pin 318 extending radially from the shaft 306, and its lower end anchored to one of the slide rods 314 to hold

the pin 312 yieldingly against one of the ends of its recess and thereby hold the pad 300 in an initial position from which it can tilt upon engagement with the platform unit P. The lower end 5 portions of the slide rods 314 are secured to bosses 320 on the ends of a cross bar 322. The rods 314 are slidable in vertical guideways formed in bosses 324 formed on the ends of a stationary bracket 326 which is secured to the end of the head 38.

Operation of the presser pad 300 is effected through a lever 328 fulcrumed upon a pin 330 (Fig. 1) secured in the head 38. The lever 328 is normally held up by a spring 332 anchored to the head 38, the upward movement of the lever 15 being stopped by the engagement of the bosses 320 with the lower ends of the bosses 324. Formed in the free end portion of the lever 328 is a slot 334 (Fig. 1) which engages a pin 336 extending through bores in a pair of ears 338 depending 20 from the cross bar 322 (Fig. 10). A treadle (not shown) connected by a rod 340 to the lever 328 enables the operator to depress the pad 300.

The turning horn 302 is secured upon the upper portion of a slide 342 which is clamped by screws 25 344 in a vertical guideway formed in the stationary bracket 326. The screws 344 extend through a vertical slot 346 formed in the slide 342 to provide for heightwise adjustment of the turning horn. The horn itself (Fig. 16) consists 30 of a U-shaped piece of sheet metal having welded to its inner central portion a wedge 348. The upper edge of the wedge 348 is thin, so that as the toe end of the lasted shoe descends, the wedge 348 will exert a heelward thrust against the toe 35 end of the last L and push the last heelwardly far enough to enable the horn 302 to clear the stitching which joins the platform cover to the sock lining. A central hollow 348 (i. e., concavity as seen in horizontal cross section) in the 40 wedge 348 provides a bearing surface for contact with the convex surface of the last.

To facilitate proper positioning of the lasted shoe for engagement of the toe end of the platform cover C with the horn 302, there is provided a stop 350 (Fig. 1) secured to the slide 342 and engageable with that portion of the unturned platform cover C which overlies the toe 45 end of the last.

The operation of the machine will now be explained. First, the last with the shoe thereon is mounted on the last pin 40 and the toe rest 42, and is then pushed by the hand of the operator heelwardly along the guideway 22 into the position shown in Fig. 1. During this heelward movement, the heel portion of the last L engages the 55 V-shaped notch of the centering gage plate 86 (Fig. 2), causing the shoe to be centered transversely as the block 46 slides in the transverse groove 56. Such transverse centering of the shoe is desirable because of the difference between rights and lefts. The springs 100 yield to permit the shoe to be pushed far enough heelwardly to insure that the horn 140, in descending, will enter within the upturned heel end of the platform cover C. Such descent of the horn 140 is effected by a downward movement of the handle 152. Now, with the horn 140 inside the platform cover and held yieldingly down against the sock lining S by the spring 172, the operator 60 grips the handles 186 to spread the horn 140 wide enough to receive the heel portion of the platform unit P. He then depresses the treadle connected to the rod 134, thereby bringing the arms 124 into engagement with the rolls 68 and 65 causing the shoe to advance toewardly until the 70 75

heelward end of the horn 140 slides just over the heelward end of the stitching which joins the sock lining and the platform cover. While the shoe is in this position, the operator lays the platform unit P in proper position upon the sock lining S. He then swings the handle 278 down, bringing the pad 204, the rod 218, and the bar 226 down (see Fig. 8) against the platform unit P and causing them to bear upon the platform unit with a heavy pressure exerted through the toggle mechanism of the pressing device 32. This pressure causes the adjacent surfaces of the sock lining and the platform unit, which already have been coated with a pressure-activated cement, to adhere. For reasons already mentioned, the device 32 will maintain its pressure even after the operator lets go of the handle 278. While the platform unit is thus held down by the pressing device 32, the operator raises the handle 152 to withdraw the horn 140 up from between the heel H and the platform cover C. He then raises the handle 278 to release the pressing device 32 and return it to its initial position.

The platform unit P having thus been applied, the operator now rocks the shoe about the axis of the arcuate guideway formed in the block 46 to raise the toe portion of the shoe off the toe rest 42, and he also pushes the shoe toewards along the guideway 22 until the toe end of the platform cover (which is still unturned) strikes against the stop 350. The shoe is now positioned so that, by its own weight (aided if necessary by light manual pressure) it will drop into the position shown in Fig. 9, the rounded toe end of the last serving as a cam to guide the horn 302 between the last and the platform cover. By depressing the treadle connected to the rod 340, the operator causes the pad 300 to push the toe end of the shoe down, thereby causing the toe portion of the platform cover to be turned over the horn 302, as shown in Fig. 11, into upstanding right-sideout position, as shown in Fig. 12. The operator then releases the treadle connected to the rod 340. The operation is now complete and the shoe and last can be removed from the machine.

In the modified machine shown in Figs. 13, 14, and 15, the platform cover turning mechanism 34 has been placed at the right-hand end of the machine rather than at the left and the device 28 for conforming the heel portions of the platform cover and the sock lining has been replaced by the device 30. This alternative device 30 comprises a cross bar 352 having its ends rigidly secured to the forward upper ends of a pair of parallel arms 354, the lower and heelward ends of which are fulcrumed upon a pair of coaxial pins 356 secured in the bracket walls 106. Depending from the central portion of the cross bar 352 and rigidly secured thereto is an arcuate lug 358 having formed on its under surface ratchet-like teeth 360 adapted to engage the upper surface of the heel H and to hold the heel as well as the entire platform unit against toewards movement when the shoe is urged toewards. The cross bar 352 and the lug 358 are normally held up in an out-of-the-way position by a cam 362 having its lower surface engageable with a curved end portion on the rear of one of the arms 124. This cam 362 is pivotally clamped for purposes of angular adjustment by a screw 364 to the lower end of a slide 366 (omitted in Fig. 14 for clarity). A guideway formed by a pair of lugs 368 on one of the arms 354 provides for movement of adjustment of the

slide 366. A screw 370 threaded into the arm 354 and extending through a slot 372 in the slide 366 serves to clamp the bar in its adjusted position. To facilitate accurate angular adjustment 5 of the cam 362 about its pivot 364, the slide 366 has a lug 374 through which is threaded a screw 376 having its lower end engageable with a lug 378 extending laterally from the cam 362. The cam 362 is yieldingly held in engagement with the arm 124 by a spring 380 attached at its upper end to one of the arms 354 and anchored at its lower end to the bracket 108.

While the treadle rod 134 is in its normal up position, the arm 124 will hold the cross bar 352 and the toothed lug 358 up out of engagement with the heel H. Then, when the operator depresses the treadle connected to the rod 134 to urge the shoe toewards, the advancing arm 124 will permit the spring 380 to draw the toothed lug 358 down into engagement with the heel and thereby cause the teeth 360 to hold the heel against toewards movement. The treadle is depressed far enough to cause the heel portions of the upturned platform cover C and the sock lining S to be conformed to the shape of the heel itself and to bring the shoe into proper toewards and heelward relationship to the platform unit. Release of the treadle thereupon serves to raise the cross bar 352 and the toothed lug 358 out of contact with the heel H. A stop pin 382 (Fig. 15), engageable with a tail on one of the arms 354, prevents excessive downward movement of the cross bar 352 if the treadle should be depressed when no work is in the machine.

The mechanism 32 for pressing the platform unit against the sock lining, while not shown in Figs. 13, 14, and 15, can be used in conjunction with the device 30 provided the shank presser cross bar 226 (Fig. 8) of that device be removed. 35 This presser cross bar is rendered unnecessary by reason of the fact that the toothed lug 358 exerts a downward component of pressure which serves equally well. Upon release of the shoe from the forming device 30 and the pressing device 32, the operator will proceed to turn the toe portion of the platform cover C in the manner already described.

Having thus described my invention, what I claim as new and desire to secure by Letters Patent of the United States is:

1. In a machine for use in the manufacture of shoes, a support for a last on which is mounted a partially completed platform shoe having an upper, a sock lining, and a platform cover united by stitching, the heel portion of the platform cover having been turned right side out to form a pocket and the forepart of the platform cover being still unturned and wrong side out, a guideway along which the support is movable between two stations, a member fixed against movement in a direction lengthwise of the guideway for causing the heel portions of the platform cover and the sock lining to be conformed to the shape of the heel seat of the last upon relative movement between said fixed member and the support, means for urging the support along the guideway to effect said relative movement and thereby to facilitate the laying of the heel end of a platform unit on the heel end of the sock lining, and means at the other station for turning the forepart of the platform cover into right-side-out position.

2. In a machine for use in the manufacture of shoes, a support for a partially completed platform shoe having an upper, a sock lining, and a

platform cover united by stitching, the platform cover having been turned right side out at its heel portion and being still unturned at its toe portion, a guideway along which the shoe support is movable between a platform unit laying station and a platform cover turning station, means at the platform unit laying station for urging the shoe support along the guideway while holding back the heel portion of the platform cover to facilitate the laying of a platform unit upon the sock lining, means at the platform unit laying station for pressing the platform unit upon the sock lining to cause pre cemented surfaces of the platform unit and the sock lining to adhere, and means at the platform cover turning station for turning the toe portion of the platform cover after the platform unit has been laid.

3. In a machine for use in the manufacture of shoes, an upstanding last pin for engagement with an inverted last on which is mounted a partially completed platform shoe having an upper, a sock lining, and a platform cover united by stitching, a carriage for supporting the last pin, a guideway along which the carriage is movable between two stations, means at one of the stations for pressing a platform unit upon the sock lining to cause pre cemented surfaces of the platform unit and the sock lining to adhere, a toe rest for supporting the forepart of the shoe against the pressure of said pressing means, a second carriage movable along the guideway for supporting the toe rest, a yieldable connection for moving the toe rest carriage along the guideway in unison with the last pin carriage, and means at the other station for turning the toe portion of the platform cover after the platform unit has been laid, said yieldable connection serving to permit the second carriage to stop in an out-of-the-way position while the first-mentioned carriage is completing its movement to bring the toe portion of the shoe into position for operation by said platform cover turning means.

4. In a machine for use in the manufacture of shoes, a support for a partially completed platform shoe having an upper, a sock lining, and a platform cover united by stitching, a carriage on which said shoe support is indirectly mounted, a guideway along which the carriage is movable between two stations, means at one of the stations for pressing a platform unit upon the sock lining to cause pre cemented surfaces of the platform unit and the sock lining to adhere, means at the other station for turning the toe portion of the platform cover, said carriage and said shoe support being constructed and arranged for adjustment of the shoe support on the carriage in a direction transverse to the guideway, and means operable upon movement of the shoe along the guideway for effecting said adjustment to center the shoe.

5. In a two-station machine for use in the manufacture of shoes, mechanism at one of the stations for operating upon a partially completed shoe, mechanism at the other station for operating further upon the shoe, a guideway extending between the two stations, a carriage movable along the guideway, said carriage having formed in it a guideway transverse to the first-mentioned guideway, a shoe support movable relatively to the carriage in the transverse guideway and movable with the carriage along the first-mentioned guideway, and a member having a pair of converging cam surfaces engageable with the heel end of the shoe for moving the shoe and its support in the transverse guideway

to center the shoe as the shoe and the carriage are moved along the first-mentioned guideway.

6. In a two-station machine for use in the manufacture of shoes, mechanism at one of the stations for operating upon a partially completed shoe, mechanism at the other station for operating further upon the shoe, a guideway extending between the two stations, a carriage movable along the guideway, said carriage having formed in it a guideway transverse to the first-mentioned guideway, a shoe support movable relatively to the carriage in the transverse guideway and movable with the carriage along the first-mentioned guideway, a centering gage operable upon engagement with the shoe to move the shoe and its support in the transverse guideway to center the shoe, and resilient means for yieldably holding the centering gage against the shoe regardless of the exact position of the carriage along the first-mentioned guideway.

7. In a machine for use in the manufacture of shoes, a support for a partially completed platform shoe having an upper, a sock lining, and a platform cover united by stitching, the platform cover having been turned right side out at its heel portion, a guideway along which the shoe support is movable, means for urging the shoe support toewardly along the guideway, a member engageable with a platform unit which rests upon the sock lining to hold the platform unit back against the turned heel portion of the platform cover as the shoe support is urged toewardly, and means operated by said urging means for normally maintaining said holding member up out of the way and for enabling said holding member to descend into operative position when the shoe support is moved toewardly.

8. In a machine for use in the manufacture of shoes, a support for a partially completed platform shoe having an upper, a sock lining, and a platform cover united by stitching, the platform cover having been turned right side out at its heel portion, means for moving the shoe support forwardly, means for holding back the heel portion of the platform cover to facilitate the laying of a platform unit on the sock lining, and means for creating pressure between the platform unit and the sock lining to cause adjacent pre cemented surfaces of the platform unit and the sock lining to adhere.

9. In a machine for use in the manufacture of shoes, a support for a last on which is mounted a partially completed platform shoe having an upper, a sock lining, and a platform cover united by stitching, the heel position of the platform cover having been turned right side out to form a pocket, means for moving the last support forwardly, means for holding back the heel portions of the platform cover and the sock lining to cause them to be conformed to the shape of the heel seat of the last to facilitate the positioning of the heel end of a platform unit on the heel portion of the sock lining, and means operable thereafter and while the platform cover and the sock lining are thus conformed for creating pressure between the platform unit and the sock lining to cause adjacent pre cemented surfaces of the platform unit and the sock lining to adhere.

10. In a machine for use in the manufacture of shoes, a support for a last on which is mounted a partially completed platform shoe having an upper, a sock lining, and a platform cover united by stitching, the heel portion of the platform cover being turned right side out to form a pocket, a flexible U-shaped band movable into said

pocket, means for spreading the U-shaped band within the pocket to widen the pocket, means for urging the last toewardly, means for the holding U-shaped band back against the force of said urging means to create a heelward thrust against the pocket formed by the platform cover and thereby to facilitate the laying of a platform unit upon the sock lining, and means for pressing the platform unit against the sock lining to cause adjacent pre cemented surfaces of each to adhere.

11. In a machine for use in the manufacture of shoes, a support for a last on which is mounted a partially completed platform shoe having an upper, a sock lining, and a platform cover united by stitching, the heel portion of the platform cover being turned right side out to form a pocket, means for urging the last support toewardly, means engageable with a platform unit which rests upon the sock lining to hold the platform unit back as said urging means forces the heelward end of the pocket against the heelward end of the platform unit to insure proper relative positioning of the platform unit and the sock lining, and means for pressing the platform unit against the sock lining to cause adjacent pre cemented surfaces of each to adhere while they are in proper relative position.

12. In a machine for use in the manufacture of shoes, a support for a last on which is mounted a partially completed platform shoe having an upper, a sock lining, and a platform cover united by stitching, a turning horn adapted to be engaged within the toe end of the unturned platform cover, said horn consisting of a U-shaped piece of sheet metal having fixed centrally thereto a wedge adapted to push the last heelwardly upon relative heightwise movement between the horn and the last support, said relative heightwise movement serving to cause the toe portion

10

of the platform cover to be turned and said heelward push of the last serving to cause the horn to clear the stitching which joins the platform cover to the sock lining, and means for effecting said relative heightwise movement between the horn and the last support.

13. In a machine for use in the manufacture of shoes, an upstanding last pin for engagement with an inverted last on which is mounted a partially completed platform shoe having an upper, a sock lining, and a platform cover united by stitching, a carriage for supporting the last pin, a guideway along which the carriage is movable between two stations, means at one of the stations for pressing a platform unit upon the sock lining to cause pre cemented surfaces of the platform unit and the sock lining to adhere, a toe rest for supporting the forepart of the shoe against the pressure of said pressing means, an upstanding stationary horn at the other station engageable within the platform cover at the toe end of the shoe, a connection between the last pin and the carriage for enabling the shoe and last to be rocked to raise the toe portion off the toe rest for presentation of the platform cover to the horn, and means for pushing the toe end of the shoe and last down to cause the toe portion of the platform cover to be turned over the horn.

of the platform cover to be turned and said heelward push of the last serving to cause the horn to clear the stitching which joins the platform cover to the sock lining, and means for effecting said relative heightwise movement between the horn and the last support.

13. In a machine for use in the manufacture of shoes, an upstanding last pin for engagement with an inverted last on which is mounted a partially completed platform shoe having an upper, a sock lining, and a platform cover united by stitching, a carriage for supporting the last pin, a guideway along which the carriage is movable between two stations, means at one of the stations for pressing a platform unit upon the sock lining to cause pre cemented surfaces of the platform unit and the sock lining to adhere, a toe rest for supporting the forepart of the shoe against the pressure of said pressing means, an upstanding stationary horn at the other station engageable within the platform cover at the toe end of the shoe, a connection between the last pin and the carriage for enabling the shoe and last to be rocked to raise the toe portion off the toe rest for presentation of the platform cover to the horn, and means for pushing the toe end of the shoe and last down to cause the toe portion of the platform cover to be turned over the horn.

PAUL W. SENFLEBEN.
